APPARATUS FOR THE PHOTOGRAPHIC REPRODUCTION OF TYPOGRAPHIC COMPOSITIONS

Eduardo Rolando Dubuisson, Av. Jose Antonio 594 bis,
Barcelona, SpainFiled Nov. 25, 1958, Ser. No. 776,374
Claims priority, application Spain Dec. 9, 1957
15 Claims. (Cl. 95—4.5)

This invention relates to apparatus for the photographic reproduction of typographic compositions.

In apparatus provided according to the invention an accurate and mechanical resolution is obtained for each line typed in a typewriter and for each line of typographic composition produced on a perforated photographic film such that the film can be cut and exactly replaced by another film if required.

The system according to the invention is of considerable use in the printing art, and especially for newspapers, since a writer can be placed in direct communication with the newspaper editor who can make any amendments he desires and who can, without further handling, pass the typographic composition produced on the photographic film to the printing room. The apparatus according to the invention also reduces editing costs considerably.

According to the present invention there is provided apparatus for the photographic reproduction of typographic compositions, said apparatus comprising: a keyboard having a plurality of keys each corresponding to a predetermined character; a rotatable drum for mechanically recording information fed by the keyboard, said drum including a plurality of discs and each disc having a plurality of radially displaceable pins co-operating with said keys; a cylindrical drum mounted for rotation about its axis, said cylindrical drum having on its curved surface a plurality of spaced and parallel transparent strips, each strip including a series of signs of predetermined size and style; photographic means including a camera mounted opposite said cylindrical drum, lens and shutter means between the camera and said cylindrical drum for feeding into the camera signs on said strips; means for producing relative movement of the photographic means parallel to the axis of said cylindrical drum to position the lens and shutter means opposite any one strip of the cylinder; and electro-mechanical means for arranging the information recorded on the rotatable drum and for transmitting the arranged information to the cylinder for photographic reproduction.

The present invention also provides apparatus for the photographic reproduction of typographic compositions, said apparatus comprising a keyboard which can be operated directly, or remotely from the keyboard of a conventional typewriter, by appropriate electrical connection means; an electro-mechanical arrangement connected to said keyboard and comprising spacer wedge elements or rod elements displaceable perpendicularly to a graduated rule or scale adapted to control and limit the advance of the writing, which rods, by automatically entering the free spaces between words and signs, are adapted to increase said spaces to justify each line, the justification of the length of each line being accomplished by automatically adding together the successive spaces occurring in each line and when necessary increasing this total space by an amount required to complete one line; a rotary drum which can act as a mechanical memory and which comprises a plurality of discs each having stops which can be displaced diametrically in dependence upon the key depressions of said keyboard and in accordance with the depressed signs and letters; a transparent drum which is rotatable around its axis and the surface of which is provided in a plurality of spaced circles parallel

2

with one another, with all the signs of a predetermined style and size and which is adapted to perform angular rotations in dependence upon the location of the stops selected in said rotary drum; a photographic lens with its corresponding shutter, placed opposite said transparent cylinder and with its optical axis coinciding with the radial extension of a diameter of the cylinder; a photographic camera which can be moved, horizontally with relation to the vertical axis of the transparent cylinder, by amounts proportional to the justification effected on said keyboard for each typed line; automatic means for perforating the film laterally at the start and end of each photographed line; and an electro-mechanical means for synchronizing the foregoing elements and governed by general keys and end-of-line control keys, for changing the letter style, releasing the mechanical memory, non-use of a line stored therein and connection for utilisation thereof.

For a better understanding of the invention and to show how the same may be carried into effect, reference will now be made to the accompanying drawings in which:

FIGURE 18 is a section on line F—F of FIGURE 16, and

FIGURE 19 is a section on line G—G of FIGURE 16.

According to the invention, it is possible to select characters in desired sequence by means of a keyboard

15 (FIGURE 1) or by operating the keys of an ordinary typewriter electrically connected to the keyboard 15, whereby solenoids or electromagnets 16 are energized which actuate levers 17 to operate pins 18, the same being thrust outwards from discs 19 of which eighty-six or more are provided, depending upon the required number of characters, and which form what can be called a "mechanical memory." The set of discs 19 rotates, in the direction indicated by an arrow 5, one step at a time when one of the keys is depressed, under the control of a pawl or an escapement mechanism 20 (FIGURE 8) and is driven by a small electric motor 2 (FIGURE 11)

which is connected to the shaft of the discs 19 by way of a clutch 3 (FIGURE 11). Each letter or sign is associated with one disc and one key.

The arm 21, at the same time as it projects the pin 18, actuates the shaft 22 which, by means of an arm 23 and pawl 44 and a gear 24 in engagement with a worm 25, adds the thickness or breadth of the selected character on the scale 26 (FIGURE 11). Scale 26 is provided with an index 27 for denoting the measurement. The index 27 is associated with an audible or visible warning signal.

Inter-word spaces are controlled by wedge-shaped elements 28 (FIGURE 15) which, by means of a corresponding space key 7 (FIGURE 7), gear 29 and worm 30 (FIGURE 11), are moved to the right one at a time, moving along with them the needle 31 (FIGURE 11) which moves along the scale 26. The spaces are added up from left to right and only those which have issued from the space store 32 will operate, because the rods thereof are in a rigid position. These rods, like the justifying rods 33, consist of strips with a knurled edge along which the wedges 28 slide. The space key 7, at the same time as it moves a wedge, moves out a pin in the corresponding disc and acts not upon the pawl 44 but upon the pawl 20 (FIGURE 8) in order that the discs may be moved without any effect on the scale 26.

After a line has been recorded in the mechanical memory, the key 34 (FIGURE 11) is depressed to energize a solenoid 35 which operates a clutch 36 and, by way of worms or worm shafts 37, 38, the space wedges which have engaged in the justifying rods 33 are urged in the direction indicated by arrows 4 and move the pointer 31 until the same abuts the index 27, the line thus being justified. The rod 39, moved by the rod 33, operates the eccentric 40, the extent of which is exactly equal to that of the space wedge 28, so that whenever a pin of the space disc operates on the solenoid 42, the gear 41 receives the corresponding displacement which, by means of the worm 43, will produce the corresponding displacement of a photographic camera 8 bearing against said worm.

If a line does not require justification, the separation between words will be equal to the minimum thickness of the space wedge; on the other hand, if the space which is lacking to complete the predetermined measurement has had to be compensated for, whatever the number of inter-word spaces the eccentric 40, which is equal to one wedge, will represent the part proportional to the number of spaces.

After a line has been recorded and justified in the mechanical memory, the end-of-line key 9 (FIGURE 6) is depressed and, through the agency of the solenoid 6, releases the pawls 45 of the space gear 29 and of the scale gear 24. In addition, the pin in the corresponding disc which has been pushed out, when the line has been photographed, is effective to cause the solenoid 6' to be operated to release the pawls 45' of the space eccentric and of the camera control gear or ratchet 41, the released members being returned to their initial positions by their respective springs. The extension of the rod 39 (FIGURE 11) is then not visible below the scale 26, an indication thus being provided that the new line can now be justified. As the set of disc rotates, the pins make contact at 46, 46', 46'', 46''', with the result that the camera is moved through the agency of solenoids 47, the matrix cylinder 48 is retained by means of the surrounding solenoids 39, one of which is provided for each vertical row of letters or signs, and the camera shutter 50 is opened through the agency of the solenoid 51. If the letter or sign to be photographed is in the second, third, fourth or a higher line of the transparent type cylinder, the pin corresponding to the key indicating cursive, fat-faced type, small capitals, symbols or the like raises the latter cylinder to the corresponding height through the agency of the solenoids 52.

The matrix cylinder can have more than four type sections provided that more solenoids with the respective levers and more raising keys with their corresponding discs are added.

5 The line following the line being photographed can, if required, be recorded in the mechanical memory while the preceding line is actually being photographed. The erase rod 53 (FIGURE 5) returns the pins to the neutral position after each letter has been photographed. As a 10 new line is being recorded, the machine will photograph one letter of the preceding line each time that a key is depressed, and if the last line has less letters in it than the penultimate line, the free key 10 (FIGURE 8) is depressed to release the pawl 20 in order that the discs may 15 be rotated by the motor. When the pin corresponding to the end of the preceding line operates the contacts 46, 46', 46'', 46''' (FIGURE 6), the pawls 45 will have been 20 released, the camera being ready to photograph the new line which will be ready for justification, and the motor will have stopped; hence the connect key 13 (FIGURE 9) must be depressed to begin the recording of the next line. On the last line the free key 10 is kept depressed until the machine has finished photographing.

It should be remembered that the number of letters and 25 spaces receivable per line is determined by the number of pins making up a disc, so that the greater the diameter of the discs and therefore the greater the number of pins, the more letters and spaces can be accommodated on a line.

30 If it is required not to photograph a line, the key 11 (FIGURE 10) is depressed to raise the contacts 46, 46', 46'', 46''' so that they are not engaged by the pins, the key 10 (FIGURE 8) being depressed at the same time so that, as the set of discs rotates, the erase rod 53 (FIGURE 1) is operated.

35 The photographic camera can be loaded with more than nine metres of 19.5 cm. film or with film of other commercially available sizes. Cameras of any required size can be constructed. If a composition is required having dimensions greater than thirty-nine pica characters, the carriage can be adapted to larger cameras.

The camera slides on ball bearings 54 which are supported by two parallel members and is moved by the worm 43 in dependence upon the breadth of the corresponding 45 letters or spaces; this dimension can be set up and varied by means of screws 55 both on the camera feed shaft and on the rod actuating the scale gear 24. The gears 24, 41 are identical, as are the corresponding worms 25, 43, and the movements of both for each letter and sign 50 are also exactly equal. The left-hand part of the camera is provided with a device 56 (FIGURE 17) for graduating and controlling the movement of the film by points, from one to thirty-six or more points as may be required. The camera, after it has photographed a 55 line and is moved to the left by the pin corresponding to the end-of-line key 9 which, when the contacts 46, 46', are closed, connects one of the solenoids 47 into circuit, operates the lever 57 which moves the clutch 58 so that, when the shaft 59 rotates, a piece of film is moved on to the extent allowed by the control device 56, so that each 60 line can be photographed spaced apart from the following line, if required. When the camera returns to its initial position on the right and after the film has been moved on and the camera is in position for photographing the following line, the pin 60, when pressed by a displaceable guide 61, punches two apertures in the edges of the film exactly opposite the line to be photographed. These apertures or perforations serve as a guide for cutting out lines which contain errors and for replacing them by correct lines, the film being maintained stationary while each line is being photographed. The lever 62 of the device 56 then engages with the guide 61 and returns to its initial position ready for the next movement of the film. 65 70 75 To the right of the camera is a small line counter 14

which operates independently of the size of body used in the composition.

The front 63 of the machine (FIGURE 2) covering the set of discs forming the mechanical memory is made of a transparent plastic material and is engraved at the top with the letters and signs corresponding to each disc, with sets of vertical and horizontal lines forming a lattice, through the squares of which the pins corresponding to the last words recorded can be seen, so that if it is required to make a correction, all that is necessary is to lift the transparent cover and press the required pins into their neutral positions. The end-of-line key 9 which pushes out the pin for releasing the pawls 45 also interrupts the current to give the camera time to return to its initial position before photographing of the next line is started. When the camera is ready, the connect key 13 (FIGURE 9) is depressed so that the disc cylinder starts to move again. The pin which interrupted the current will then energise the solenoid 66 by way of the contacts 67 to release the key 13.

If a composition of mathematical formulae is required, for which purpose the film will have to be wound back, the mechanism 56 is released and the bottom knobs 12 (FIGURE 16) of the camera spool holder are operated. The amount of film wound back can be checked by operating the mechanism 56.

If a different type face is required, the nut 65 is removed and the electric lamp and the optical condenser are lifted upwards, the transparent matrix cylinder withdrawn and another cylinder placed in position.

The resultant composition can be positive or negative, depending upon whether positive or negative matrices are used.

To change the body or size of the types, the quadrant 64 is moved and the body fixed between four and thirty-six points and the corresponding lens is moved up, the lens carrier being rotated or changed. Alternatively matrices having different faces and the corresponding lenses can be used. All the necessary lenses can be adapted. The quadrant 64 acts on the levers controlling the scale gear 24 and film feed gear 41 by means of eccentrics operated by the same worm shaft.

Each disc has eighty or more pins so that with relatively large type bodies the maximum measurement provided corresponds to one complete revolution. With the smaller bodies it is not customary to use large composition measurements because reading becomes difficult, and so larger discs are not needed. Nevertheless, a composition consisting of thirty-nine pica characters, body four, can be produced. To this end, the composition is broken down into smaller dimensions of an equivalent sum without any operation of the end-of-line key 9, so that the camera does not return to its initial position, whereafter the key 9 is depressed and justification is effected at the end of the last section.

The matrix cylinder is moved by the same motor as that which drives the set of discs, by way of a sliding disc clutch 1, so that when the cylinder is braked by the solenoid corresponding to each letter, the same is positioned correctly opposite the lens and the lighting system.

For normal composition only ten different letter breadths are required, so that these can be obtained using only ten solenoids to control the movement of the camera. However, more solenoids can be used if required.

For headlining, and although at present there is no suitable film wider than 19.5 cm. commercially available, provision has been made to use, in due course, wider cameras and carriages which can be moved backwards and forwards, with a view to using lenses for the composition of large headlines for newspapers, periodicals and other commercial work. The camera described can be used for this kind of work, the pieces of composition being cut and joined.

I claim:

1. Apparatus for the photographic reproduction of typ-

graphic compositions, said apparatus comprising a keyboard having general keys, an end-of-line control key, letter style control keys, character keys, a space key and a line cancellation key, and electrical connection means operatively coupling said apparatus keyboard to the keyboard of a conventional typewriter; an electro-mechanical device connected to said keyboard and comprising wedge-shaped elements, graduated scale control means, said wedge-shaped elements being displaceable perpendicularly to said graduated scale control means to control therewith and limit the advance of the typographic compositions, means actuated by the character keys for originating and transmitting a first series of signals each representative of a character in a line of typographic composition, means responsive to said signals and operatively associated with said graduated scale control means to provide a summation of the widths of the characters represented by said signals, means actuated by the space key for originating and transmitting a signal representative of a space between characters and provide a free space representation on said scale control means, said wedge-shaped elements being responsive to said last-mentioned signals to enter the free space representations to increase said spaces to justify each line; a single rotary drum including a plurality of discs each having pins displaceable diametrically in dependence upon the key depression of said apparatus keyboard and in accordance with the character keys and space key depressed, each said disc having the same number of pins as the total number of characters and spaces forming a single line of the typographic composition, each said character key and the space key of said apparatus keyboard being electro-mechanically coupled to one of said discs, a lever for each said character key and said space key, a solenoid for each said character key and said space key energizable to act on said associated lever for actuating one of said pins connected to the corresponding disc so that said pin is pushed out radially; electrical contacts rendered operative in response to the displaced pins on all of said discs, a common shaft coupled to all of said discs for turning the same simultaneously angularly in a single direction, an electric motor, a first clutch coupling said electric motor to said shaft for rotation thereof, and an escape pawl governing the angular movements of said discs; a transparent drum rotatable about its axis and the surface of said transparent drum being provided with a plurality of spaced rows parallel with one another having all the signs of a predetermined style and size, a sliding disc clutch coupling said transparent drum to said motor to impart to said transparent drum angular rotations in dependence upon the location of the displaced pins selected in said rotary drum, and electro-mechanical means responsive to said electrical contacts to permit rotation of said rotary drum; a photographic lens with its corresponding shutter, placed opposite said transparent drum and with its optical axis coinciding with the radial extension of a diameter of the transparent drum; a photographic camera, gearing coupling said camera to said transparent drum for movement relative to the axis of said transparent drum by amounts proportional to the dimensions of the typographical characters effected on said apparatus keyboard for each typed line; automatic means for perforating the film laterally at the start and end of each photographed line; and an electro-mechanical means responsive to said electrical contacts for synchronizing the foregoing elements and governed by said general keys, said end-of-line control key, said letter style control keys for changing the letter style by raising said transparent drum, and said line cancellation key to control non-use of a stored line, and connections for utilization thereof.

2. Apparatus according to claim 1, wherein said graduated scale control means comprises a graduated scale, arms for actuating the displaceable pins operable by the corresponding space key and the character keys to operate the shaft of another arm, means including a pawl, a worm and gearing in mesh with said worm, which during

rotation thereof displaces to the left said graduated scale on which the spaces corresponding to the thickness or breadth of each character are added linearly, said scale including an end-of-line stop and a warning device, said stop corresponding to the measurement which the line of typographic compositions is required to have and being operatively connected with said warning device.

3. Apparatus according to claim 2, wherein said graduated scale control means includes a space store, said space key being operatively connected to said rotary drum to push out said pins in the corresponding disc of said rotary drum and simultaneously to act upon said space store, said space store comprising strips with grooved edges serving as a guide for said wedge-shaped elements and providing a summation of the space intervals and adding them to the summation of the widths of the characters.

4. Apparatus according to claim 3, including a separate solenoid, a separate key energizing said solenoid, worm gears rotatable by said motor to move said wedge-shaped elements, wherein the typed lines can be justified automatically by depressing said special key to energize said solenoid to operate said first clutch so that the movement of said motor is transmitted to said gears which, as they rotate and advance, move said wedge-shaped elements to increase all the spaces proportionally until the displacement of the graduated scale coincides with the end-of-line stop.

5. Apparatus according to claim 4, including a transfer rod drawn by said wedge-shaped elements on to an arm the extent of which coincides with that of one of said wedge-shaped elements, and means coupled to said arm including a solenoid, gearing and a worm to control the lateral movements of said photographic camera whenever said pins raise said arm.

6. Apparatus according to claim 5, including two levers so that the typographic compositions recorded by the rotation of the pins is retransmitted to the photographic camera in two consecutive strokes by said two levers which are raised by said pins previously displaced by said arm in response to energization from corresponding solenoids, said two levers being operatively associated with said gearing coupling said camera to said transparent drum for determining the lateral displacements of the camera relatively to the optical axis of its lens in accordance with the justification of each line; and including a solenoid, and electromagnetic brakes operatively associated with said transparent drum for locking of the transparent rotating drum in accordance with the displacement of said pins, and the automatic operation of the photographic shutter is effected by said last-mentioned solenoid once the previous strokes have been made.

7. Apparatus according to claim 6, including electro-mechanical means operative in response to said end-of-line key to effect lateral return movements of the photographic camera at the end of each line to start a new line, said return movements being effected automatically in dependence upon the return movements of the controls of said keyboard, depression of said end-of-line key releasing and returning the photographic camera and wedge-shaped elements.

8. An apparatus for producing preselected and justified lines of type photographically on film or sensitized paper, comprising a keyboard each key of which corresponds to an individual character or function, a single cylindrical mechanical memory register for receiving and holding all information in the same order as transmitted from the keyboard, said register including a plurality of discs and a splined shaft, said discs being keyed side by side on said splined shaft, a plurality of pins movable coupled to each said disc for movement radially thereof, an operating blade operatively connected with each said disc to engage one of said plurality of pins on each said disc to move radially thereof the engaged pin, each disc representing one of said characters or functions separated one from another by sufficient space to permit the passage

therein of one of said operating blades, said blades project one of said pins on each of said discs, a solenoid outside said discs for each said operating blade energizable to act thereon to project said pin radially, a block of multiple contacts associated with each said disc in the front thereof and remote therefrom, a cylinder including font means thereon bearing the characters represented by said discs, means to justify a completed line of characters and to commence a next line, electro-mechanical devices rendered operative by said multiple contacts for transferring the completed justified line to said font means on said cylinder simultaneously with the transmission of the next line to said discs whereby to carry the characters represented by said discs of the completed justified line, said font means including at least two parallelly displaced bands adhered to and encircling said cylinder, a transparent material to hold thereon each character for photographic purposes and arranged on said two parallelly displaced bands, each band containing the whole of the characters represented by said discs but differing one from the other in style only of these characters, said different styles of the same characters always being in one line parallel to the axis of said cylinder, photographic means comprising a camera and gearing coupling said camera to said cylinder for movement laterally to the axis of said cylinder and synchronized electro-mechanical means for effecting such movement in response to said justifying means, means comprising interchangeable objectives according to the size of type required and a shutter between said camera and said cylinder, means for obtaining axial movement of said cylinder to place any character in front of the camera objective and shutter, means for electromechanical detection and transmission of the information registered on said mechanical memory register to said photographing means, and a viewing means associated with said mechanical memory register for immediate inspection thereof at any time by an operator, said last-mentioned means comprising a transparent window.

40 9. An apparatus according to claim 8, including electro-mechanical devices coupled to said keyboard, a line control including a graduated and visible scale, said blades slidable between said discs in said spaces therebetween perpendicular to the axes of same to project the ends of said pins and simultaneously add the widths of the characters typed on said keyboard, such widths being registered on said line control, means for controlling the separation between adjacent characters of a line to be photographed and adding any space in width to the normal width of the characters on said line control graduated scale and simultaneously controlling lateral movement of said camera in the same proportion, said justifying means including a line justifying system for adding spaces between words to said line control each time a 45 spacer key on said keyboard is operated and comprising two rows of wedge shaped elements arranged in one plane with the vertices of one row engaged in contact with and overlapping those of the other row, two pairs of parallel bars for supporting and locking the bases of 50 said wedge shaped elements, one pair of said parallel bars being fixed and constituting a space bar store from which said wedge shaped elements slide on sliding lock supports one at a time and each time the space key is depressed to enter said other pair of parallel bars, said other pair of 55 parallel bars being aligned with said one pair of parallel bars in continuation therewith, intervening means coupled to said line justifying system for moving said other pair of parallel bars closer together when the line justifying key is depressed, an adjustable end-of-line limiting stop on said graduated scale, an index finger coupled to the first space bar transferred and slidable along said graduated scale into contact with said adjustable end of line limiting stop so that the inward movement of the two parallel bar supports slide the tapered space bars inwardly, thereby pushing said index finger into contact

with said end of line stop because of the increased thickness of each of said wedge shaped space bars, so as to justify the line.

10. An apparatus according to claim 8, comprising an escapement mounted on said splined shaft for communicating thereto by means of impulse and locking pawls predetermined fractional turning movements, and means rendering said escapement wheel inoperable so that all of said discs rotate freely, a key provided with a number of radial pins, an elongated keyway assembly for said shaft, housings for said pins in the borders of said discs positioned in perfect alignment by said prolonged keyway assembly, said pins being projected radially from their disc housings when their corresponding keys on the keyboard are depressed.

11. An apparatus according to claim 8 comprising means associated with said discs for removing said pins from their operative position and returning said pins to their neutral position as soon as their corresponding characters have been completely photographed, except when the line has to be photographed repeatedly.

12. An apparatus according to claim 8, in which said bladelike elements include an intermediate lever and pawl which also act on said ratchet wheel through said intermediate lever and said pawl each time a key representing a character or sign is depressed on the keyboard, a threaded shaft threaded into the supports of said visible scale, said ratchet wheel being fixed to said threaded shaft, said scale moving to the left through a distance proportional to the stroke of said pawl and in response to the movement of said ratchet wheel and in accordance with the width of the character or sign of the key depressed, said scale moving at the side of said fixed index finger to indicate continually the width total of the characters registered on said discs, said index finger being fixed only when the space between-word key is not operated and when operated moves said index finger to the right in a direction opposite to that of said scale when registering individual character widths.

13. An apparatus according to claim 8 including a spacer key operable to project one of said pins, a threaded shaft, a pawl and a ratchet wheel fixed at the extreme end of said threaded shaft, said spacer key actuating said pawl to rotate said ratchet wheel, said shaft upon turning moving the group of wedge-shaped-space-width bars to the right each time the spacer key is operated, one of said bars while entering two line justifying parallel bars moves said index finger to the right with respect to said graduated scale thereby adding the width of said bar to the total width of the characters already registered thereon.

14. An apparatus according to claim 8, including a system of electro-magnetic brakes comprising a number of electromagnets equal to the number of rows of characters to prevent the turning of said cylinder individually and leave its corresponding character in front of the objective to be photographed, to transmit to a film character images in accordance with the projection of said pins in two rapidly following consecutive operations, switching contacts closed by said pins to energize said electromagnets to produce step movements of the camera and successive short periods of immovability of said cylinder and means to open the shutter of said camera when the film is exposed to the character that forms part of the writing equivalent on said discs to complete the transmission of same.

15. An apparatus for producing photographically on film or sensitized paper, preselected and justified lines of type, comprising a keyboard each key of which corresponds to an individual character or function, a single cy-

lindrical rotatable register comprising a mechanical memory for receiving and holding all information in the same order as transmitted from the keyboard, said mechanical memory including a common splined shaft and a plurality of discs, said discs being keyed side by side on said shaft, a plurality of pins movable radially of each of said discs, an operating blade for each said disc coupled to said shaft for movement rotatably and radially thereof to engage one of said plurality of pins on each said disc to move radially thereof the engaged pin, each said disc representing one of said individual characters or functions and being separated one from another by sufficient space to permit the passage therebetween of one of said operating blades, a solenoid for each said operating blade energizable to act thereon to project said engaged pin radially, a block of multiple contacts positioned over each said disc, means to justify a completed line and to commence a next line, a cylinder including four parallelly disposed bands, fonts carried by said bands providing for different character styles, electro-mechanical means rendered operative by said multiple contacts for transferring the completed justified line to said fonts, means to rotate said cylinder in one direction, solenoid operated brake mechanism rendered operative in response to said electrical contacts to stop the rotation of said cylinder to photograph individual characters of the justified line, a transparent material to hold thereon each character for photographic purposes and arranged in quadruple on said four parallelly displaced bands, each band containing the whole of the characters represented by said discs but differing one from the other in the style only of these characters, said different styles of the same characters always being in one line parallel to the axis of said cylinder, photographic means comprising a camera, gearing movably coupling said camera to said cylinder for movement perpendicularly to the axis thereof, and synchronized electro-mechanical means for effecting such movement in response to said line justifying means, means comprising interchangeable objectives according to the size of type required and for changing the shutter between said camera and said cylinder, means to effect axial movement of said cylinder to change the style of characters, means for electromechanical detection and transmission of the information registered on said mechanical memory to said photographing means, and means for imparting movement to said mechanical memory and said cylinder including an electric motor, a sliding disc clutch coupling said cylinder to said motor, a variable thrust slipping clutch coupling said mechanical memory to said motor, an escapement mechanism for said plurality of discs fixed to said shaft for holding same and engageable with said discs to impart a step-by-step movement to said plurality of discs comprising the mechanical memory.
